COIN CONTROLLED VENDING MACHINE

Louis Steiner, New York, N. Y.

Application June 12, 1941, Serial No. 397,723

9 Claims. (Cl. 194—57)

This invention relates to coin controlled vending machines. It is particularly directed to coin controlled machines for vending articles stocked in a plurality of chutes.

One object of this invention is to generally improve the machine disclosed in my Patent No. 2,083,928 issued June 15, 1937, and my Patent No. 2,207,902 issued July 16, 1940.

In my Patent No. 2,083,928 there is disclosed a vending machine for vending cigarettes or other packages upon insertion into the machine of a dime and a nickel or three nickels.

In my Patent No. 2,207,902 there is disclosed a machine from which articles may be dispensed by insertion into the machine of either a dime and two nickels, or four nickels, with means to permit vending of articles from one or more chutes beginning at the left of the machine, upon insertion into the machine of a dime and a nickel. The machine disclosed in said patent could be converted from a 20¢ machine into a 15¢ machine (a dime and a nickel) with provision for dispensing articles from one or more chutes beginning at the left of the machine, upon insertion of one dime only.

The following difficulties have been found with such machines:

1. If the machine were set to operate for either 20¢ or 15¢, the adjustment to permit dispensing of articles for a nickel less could only be made either on the first chute at the left of the machine, or the first two on the left of the machine, or the first three, and so forth. The adjustment could not be made, for example, on the second chute alone, or the fourth chute, or the last chute. Said adjustment could only be made on one or more chutes beginning at the left, and therefore the use of the machine was limited to placing the cheaper cigarettes only in certain chutes.

2. The conversion of the machine from a 20¢ machine to a 15¢ machine necessitated removal of levers and replacement of parts which required the work of a mechanic, and could not be done quickly or easily.

3. The machine could in no case operate on insertion of two dimes, or three nickels.

It is therefore an object of the present invention to provide a machine of the character described, which may be converted from a 20¢ machine to a 15¢ machine by two extremely quick and easy adjustments, and which do not necessitate either replacement or removal of parts, and which can be done with the use of only a screw driver.

A further object of this invention is to provide a machine of the character described, in which any one or more of the chutes can be easily and quickly converted to operate for a nickel less than the price for which the machine is set. In other words, if the machine is set to operate for dispensing articles from the chutes for 20¢, any one or more of the chutes may be converted by a very simple adjustment to dispense articles for a nickel less, and if the machine is set to operate for 15¢, any one or more of the chutes may be as easily converted to operate for a nickel less.

In the present machine, it is not only the first, or first two, or first three chutes, and so forth, which can be operated for a nickel less, but any one or more of the chutes irrespective of its position in the machine, so that the cheaper cigarettes may be stocked in any one or more of the chutes.

Furthermore, any 20¢ operation can be effected by insertion into the machine of two dimes, a dime and two nickels or four nickels, and any 15¢ operation, upon insertion into the machine of either a dime and a nickel or three nickels.

A further object of this invention is to provide a strong, compact and durable machine of the character described, which shall be relatively inexpensive to manufacture, easy to manipulate, smooth and positive in operation, and withal practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a side elevational view of the coin controlled mechanism for a vending machine embodying the invention, set to operate for dispensing articles from the machine by insertion into the machine of either two dimes or four nickels, or one dime and two nickels;

Fig. 2 is a front elevational view of a portion of the chutes and coin controlled mechanism embodying the invention;

Fig. 3 is an enlarged, cross-sectional view taken on line 3—3 of Fig. 1;

Fig. 4 is a side elevational view similar to Fig. 1, but with the levers removed, and with parts

broken away and in cross-section, and showing two dimes inserted into the dime slot of the machine;

Fig. 5 is a view similar to Fig. 4, but showing the draw bar pulled forward to illustrate the lifting of the levers when the machine operates with two dimes inserted;

Fig. 6 is a view similar to Fig. 1, but showing the machine converted into a 15¢ machine to operate upon insertion of either a dime plus a nickel, or three nickels;

Fig. 7 is a view similar to Fig. 6, but showing the levers removed and the draw bar pulled forward when a nickel and a dime are inserted into the machine;

Fig. 8 is an enlarged, cross-sectional view taken on line 8—8 of Fig. 6;

Fig. 9 is a cross-sectional view taken on line 9—9 of Fig. 2;

Fig. 10 is a cross-sectional view taken on line 10—10 of Fig. 9;

Fig. 11 is a partial view similar to Fig. 9, but illustrating the position of the parts when one of the chutes is set to operate for a nickel less than the remainder of the chutes; and

Fig. 12 is a cross-sectional view taken on line 12—12 of Fig. 2.

Referring now in detail to the drawings, 10 designates a coin controlled vending machine embodying the invention. The machine 10 comprises a horizontal wall 11, from which there extends upwardly at the front, a wall 12, and from the rear of which there extends downwardly a wall 13. Attached to wall 11 is a downwardly extending front wall 14, aligned with wall 12. Extending upwardly from horizontal wall 12, is a row of vertical aligned chutes 16. Each chute 16 comprises a rear wall 17, side walls 18 and flanges 20, extending inwardly from the front ends of side walls 18. The chutes 16 are thus open at the front.

The top wall 11 is formed with a plurality of parallel slots 23, extending from front to rear, and centrally located with respect to the chutes 16. Slidably mounted on said wall 11, and aligned with each slot 23, is a draw bar 24 having a handle 25 at the front, a rod 26 extending from front to rear carrying said handle, and a block 27 at the rear end of rod 26 to push the lowermost package in the chute rearwardly when the draw bar is drawn forwardly and then released to be moved rearwardly under the influence of a suitable spring, as will be shown hereinafter. Fixed to each block 27, and extending downwardly through its slot 23, is a hook 28, for the purpose hereinafter appearing.

Mounted within the machine, and below wall 11, is a horizontal axle 30, to which there are pivoted crank arms 31 carrying a transverse horizontal rod 32 at their outer ends adapted to be engaged by the hooks 28. A torsion spring 35 on axle 30 has an arm 36 engaging rod 32 and tending to move the rod 32 rearwardly. Thus, when a draw bar is pulled forwardly, the rod 32 will be moved forwardly to permit the lowermost package in the chute to drop in the chute. When the draw bar is released, spring 35 pushes rod 32 rearwardly to push the draw bar which has been drawn forwardly, in a rearward direction to eject the dropped package.

Twenty cents coin control mechanism

Means is provided to prevent any draw bar from being pulled forwardly unless the proper

coins are deposited into the machine. To this end, the machine 10 is provided with a side wall 40 disposed below wall 11 and formed with a horizontal slot 41. Fixed to the outside of the side wall 40 is a member 43 formed with a groove 44 in which is slidably mounted a slider plate 45. Attached to the slider plate 45 is a pin 46 passing through slot 41 and connected by link 46a to arm 31. Thus, when a draw bar is pulled forwardly, it slidably moves slider plate 45 forwardly. If the slider plate 45 is held against movement, no draw bar can be pulled forwardly.

The coin controlled mechanism includes suitable means to hold plate 45 against forward movement unless the proper coins are deposited. Plate 45 is formed with a slot 47 enlarged downwardly at its forward end to form a shoulder or stop 48. Above slot 47 is a horizontal slot 49. In the forward part of the plate is a slot 50 enlarged downwardly at its lower end to form a shoulder or stop 51. Above slot 50 is a substantially similar slot 52 enlarged downwardly at its forward end to form a shoulder or slot 53.

At the forward end of plate 45 is an upwardly extending portion 54 formed with a slot 55 disposed above slot 52. Plate 45 is retained within the groove 44 by a vertical plate 57 attached at its upper and lower ends to member 43; and also by a vertical member 59 slidably mounted on member 43 adjacent the forward end thereof. Member 59 is formed with slots 60 to receive screws 61 screwed to member 43, the heads of said screws engaging the outer surface of member 59 to permit said member to slide upwardly and downwardly.

Mounted on the side of the machine above member 43, is a member 64 provided with a dime chute 65 and a nickel chute 66 to receive, respectively, dimes and nickels inserted into the machine. Plate 45 is furthermore formed with grooves 65a, 65b and 65c above slot 49, between slots 47 and 49 and below slot 47, respectively, aligned with the chute 65. Thus, when a dime drops into chute 65 it will pass downwardly through groove 65a and 65b into groove 65c.

Slidably mounted on member 43 and below plate 45, is a horizontal coin release bar 79 on which the coins come to rest when dropped into the chute. Thus, the first dime inserted into the chute will rest on bar 79. The second dime inserted into the chute will rest on top of the first dime.

Plate 45 is furthermore formed with grooves 66a, 66b, 66c and 66d disposed above slot 55, between slots 52 and 55, between slots 50 and 52 and below slot 50, respectively. When a nickel is inserted into chute 66, it will drop through through grooves 66a, 66b and 66c into groove 66d to rest on the release bar 79. The second nickel passes through said grooves to rest on the first nickel. The third nickel rests on the second nickel, and the fourth nickel will rest on the third nickel.

Pivoted to member 43, as at 71, is a lever 72 formed with an offset lug 73 projecting into slot 47, and adapted to be engaged by shoulder 48 to prevent forward movement of plate 45. If a dime is inserted into the chute, forward movement of slide plate 45 will cause the dime to engage lug 73 to rotate lever 72 upwardly to bring said lug above the shoulder. Lever 72 is normally pulled downwardly by a spring 74 interconnecting the rear end of the spring with the machine. The lever may be formed with a slot 75 through which there passes a guide screw or pin 76 fixed to bar 57.

Pivoted to bar 57, as at 78a, is a second lever 78 formed with an offset lug 79 projecting into slot 49; and also with a second lug 80 projecting into slot 50 and adapted to engage shoulder 51 to prevent forward sliding movement of plate 45. A second dime inserted into the machine, however, will rest on the first dime and will engage the lug 79 to raise lever 78 when a draw bar is pulled forwardly to disengage the lug 80 from shoulder 51.

Furthermore, the first nickel inserted into the machine will be adapted to engage the lug 80 to lift the lever 78 and disengage said lug from said shoulder 51. Thus, lever 78 will release plate 45 either upon insertion of a second dime or a first nickel. Lever 78 is normally pulled downwardly by a spring 81 interconnecting the forward end of said lever with the rear end of lever 72. Said lever may be formed adjacent its forward end with a slot 83 to receive a guide pin or screw 84 fixed to the machine.

There is furthermore pivoted to bar 57, as at 85, a third lever 86 provided with an offset lug 87 projecting into slot 49 just in front of the lug 79; and also formed with a second offset lug 88 projecting into slot 52 and adapted to engage the shoulder 53 to prevent forward movement of the slider plate 45. Lever 86 will be swung upwardly, however, to release the plate 45 upon insertion into the machine of either two dimes or two nickels. Thus, a second dime will engage lug 87 to lift the lever; or a second nickel will engage lug 88 to lift said lever. Lever 86 is normally pulled downwardly by a spring 90 interconnecting the forward end of the lever with pin 84. Said lever may also be formed with a slot 91 at its forward end to receive a guide pin 92 fixed to the machine.

There is furthermore pivoted to bar 57, as at 93, a fourth lever 94 provided with a lug 95 disposed at such a height that said lug will be engaged by the fourth nickel inserted into the machine to lift said lever upon drawing forward a pull bar. Lever 94 is interconnected to lever 72 by a link 96. Thus, upward movement of lever 94 will cause upward movement of lever 72 to release lug 73 from shoulder 48. Thus, lug 73 will release shoulder 48 by insertion of either a dime or four nickels.

It will now be understood that slider plate 45 will be totally released by insertion into the machine of either two dimes or a dime plus two nickels, or four nickels. If two dimes are inserted, the first dime releases lug 73 from shoulder 48 and the second dime releases lugs 80 and 88 from shoulders 51 and 53, respectively. If a dime and two nickels are inserted into the machine, the first dime releases lug 73 from shoulder 48. The first nickel releases lug 80 from shoulder 51; and the second nickel releases lug 88 from shoulder 53.

If four nickels are inserted into the machine, the first nickel releases lug 80 from shoulder 51. The second nickel releases lug 88 from shoulder 53, and the fourth nickel causes upward swing of lever 94 and hence lever 72 to release lug 73 from shoulder 48 to permit the slider 45 to be pulled forwardly.

It will now be understood that articles from any of the chutes may be dispensed upon insertion into the machine of either two dimes, a dime and two nickels or four nickels.

Conversion of machine from 20¢ to 15¢

Means is provided to convert the machine from

a 20¢ machine to a 15¢ machine; in other words, to permit articles to be vended upon insertion into the machine of either a dime and a nickel or three nickels. To this end, link 96 is formed with a screw threaded opening 100 located just below the lever 86. Screwed into said opening is a screw 101. On said lever is a lock nut 102. When the machine operates as a 20¢ machine, the screw is in the position shown in Fig. 3 of the drawings. In such position, the screw 101 is screwed back to clear the lever 86 so that as levers 94 and 72 swing upwardly, lever 86 will not be contacted by screw 101. To convert the machine from a 20¢ machine to a 15¢ machine, the lock nut 102 is released and the screw 101 is then screwed inwardly to the position shown in Fig. 8, and the lock nut then again tightened. The screw is then beneath lever 86 so that either lever 94 or 72 is swung upwardly, lever 86 will swing upwardly therewith.

There is furthermore pivoted to lever 94, as at 105, adjacent the pivot 93, a lever 106. Screwed to lever 94 is a headed guide screw 94a passing through a slot 107 in lever 106. Lever 94 is formed with a substantially rectangular opening 110, and extending from lever 106, is an offset lug 112 projecting through the opening 110, and so positioned as to be engaged by a third nickel inserted into the machine, when lever 106 is down, as shown in Fig. 6.

When the machine is set to operate for 20¢, movement of lever 106 relative to lever 94, does not have any effect on lever 94. Means is provided, however, to fix lever 106 to lever 94, so that upward movement of the former will cause corresponding upward movement of the latter, upon insertion of three nickels into the machine. To this end, lever 94 is formed adjacent its upper end with an upwardly projecting portion 115, to the upper end of which there is pivoted, as at 116, a bell crank 117.

When the machine operates for 20¢, the bell crank 117 is in a position shown in Fig. 1 of the drawings, and does not engage the lever 106. The lever 106 is formed with an offset lug 120 adapted to be engaged by the bell crank 117 when said bell crank is moved from the position shown in Fig. 1 to the position shown in Fig. 6. The change in the position of the bell crank may be made by first loosening the screw 116, then swinging the bell crank to the position shown in Fig. 6, and then again tightening the screw. Said bell crank may be formed with a forwardly extending finger engaging handle 122 to facilitate rotation of said bell crank. When the bell crank is rotated to engage the lug 120, lever 106 will move with lever 94. The insertion of three nickels into the machine will then raise lever 106 and consequently lever 94 and hence lever 72, when a draw bar is pulled forwardly.

It will now be understood that when the two adjustments described above have been made, the machine will be converted from a 20¢ machine to a 15¢ machine, and will operate upon insertion into the machine of either a dime plus a nickel, or three nickels. When a dime and a nickel are inserted into the machine, the first dime will raise lever 72 and disengage lug 73 from shoulder 48. Furthermore, the screw 101 will raise the lever 86 to disengage lug 88 from shoulder 53. The nickel will cause disengagement of lug 80 from shoulder 51.

When three nickels are inserted, the first nickel will disengage lug 80 from shoulder 51. The second nickel will disengage 88 from shoulder 53,

and the third nickel will cause levers 106, 94 and 72 to move upwardly to disengage lug 73 from shoulder 48.

Conversion to permit any chute or combination of chutes to operate for a dime plus a nickel when the machine is set for 20¢, and to permit any chute or combination of chutes to operate for a dime when the machine is set for 15¢

Means is provided to permit dispensing of articles from any one or more of the chutes for a dime plus a nickel when the machine is set to operate for 20¢, and for a dime only when the machine is set to operate for 15¢.

To this end, there is fixed to the underside of horizontal wall 11, as by rivets 130, a plurality of spaced brackets 131, each bracket being disposed between a pair of adjacent draw bars. Each bracket 131 has a downwardly extending front wall 133 formed with a slot 134 and a rearwardly extending downwardly depressed tongue or shelf 135. Fixed to said wall 11, and in alignment with each of the brackets 131, and extending downwardly therefrom is a headed pivot pin or rivet 137. Pivoted to each pin 137 is a plate 138, the forward end of which rests on the tongue 135. Plates 138 are for the purpose of preventing more than one draw bar from being pulled forward at a time, as described in my Patent No. 2,207,902.

There is furthermore pivoted to each pivot pin 137, a cam plate 140 disposed below plate 138, and having a forwardly extending tongue 141 projecting through slot 134, and formed at its forward end with an opening 142. Each plate 140 has an offset cammed portion 143.

As shown in Fig. 9 of the drawings, the cammed portions 143 extend to the left of each member 140 and are adapted to be engaged by the hook portion 28 of the draw bar disposed on the left of said member when said draw bar is pulled forwardly. When a draw bar is pulled forwardly, the cam plate 140 on the right thereof will be swung in a counterclockwise direction looking at Fig. 9 of the drawings. The cam plates 140 do not normally effect ejection of articles from any of the chutes at the price for which the machine is set, but become effective only for the chutes from which articles are to be dispensed for five cents less than the price for which the machine is set.

Horizontal wall 11 is formed adjacent the front thereof with an opening 145, located just forwardly of each bracket 131. The upper end of wall 14 may be formed with a rearwardly extending flange, notched as at 146, to register with the openings 145. Slidably mounted on top of wall 11 is a transverse elongated bar 150 formed with a screw threaded opening 151 aligned with the opening 142 of each cam plate 140. Any suitable guide brackets 152 may be attached to wall 11 to guide the bar 150.

Extending upwardly from the left end of bar 150 is an arm 153 interconnected to a bracket 154 on the machine by a coil compression spring 155, which normally urges bar 150 to the left. Fixed to arm 153 is a cam 156 having an upwardly and outwardly inclined edge 157. The cam 156 passes through an opening 158 in the slidably mounted plate 59. Fixed to the upper end of plate 59 is a pin 159 disposed above the inclined edge 157 of cam 156.

If the bar 150 is not connected to any of the cam plates 140, said bar will remain at its left handed position, as shown in Fig. 2 of the draw-

ings and will not raise the bar 59, and thus is entirely ineffective. However, if it is desired to vend articles from any chute or chutes for 5¢ less than the price for which the machine is set, then the bar 150 is connected to the cam plate or plates at the right of said chute or chutes by means of pin or pins 160. Pin 160 has a screw threaded portion at its upper end screwed within the screw threaded opening 151 of the bar, the lower end of said pin passing through the opening 142 in the cam plate. The bar 150 may thus be connected to any one or more of the cam plates. If the bar 150 is thus connected to any one or more of the cam plates, then a pull on any draw bar on the left of said connected cam plates will cause swinging movement of said cam plate to the right, or in a counterclockwise direction, looking at Fig. 9 of the drawings, to pull the slidably mounted bar 150 to the right against the tension of spring 155 and cause the cam plate 156 to raise slidably mounted plate 59 for the purpose herein-after appearing.

If the machine is set for 20¢, then there is attached to the bar 59, a lug 162 so located as to raise the lever 86 when the draw bar is pulled. If the machine is set to operate for 15¢ the block or lug 162 is fixed to the bar 59 in the dotted line position shown in Fig. 7, to engage the lever 78 for raising the same when a draw bar at the left of any connected cam plate 140 is pulled forwardly.

Thus, if the machine is set for 20¢, chutes at the left of any connected cam plates 140 will operate upon insertion into the machine of a dime and a nickel. The dime will raise lever 72 to disengage lug 73 from shoulder 48. The nickel will raise lever 78 to disengage the lug 88 from shoulder 51 and the lug or block 162 will raise lever 86 to disengage lug 88 from shoulder 53.

If the machine is set for 15¢, chutes at the left of cam plates 140 connected to the bar 150 will operate upon insertion into the machine of one dime. Thus, the dime will disengage lug 73 from shoulder 48 and will also raise lever 86 through screw 161, to disengage lug 88 from shoulder 53. Furthermore, upward sliding movement of bar 59 will cause lug 162 to raise lever 78 to disengage lug 88 from shoulder 51.

The chutes at the left of cam plates which are not connected to the sliding bar 150 will have articles dispensed therefrom in the usual way depending upon how the machine is set, either for 20¢ or for 15¢.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In a vending machine, a movable member formed with three shoulders, a member adapted to engage one of the shoulders to prevent movement of said movable member and releasable upon insertion into the machine of a coin of one denomination, a second member having means to engage a second shoulder to prevent movement of said movable member and releasable upon insertion into the machine of a coil of

another denomination, a third member having means to engage a third shoulder and releasable upon insertion into the machine of a second coin of said other denomination, said second and third members having means to release said second and third members from the second and third shoulders upon insertion into the machine of a second coin of the first denomination, a fourth member, means to connect the first member to the fourth member for movement therewith, and means on the fourth member to engage a fourth coin of said other denomination upon insertion into the machine of third and fourth coins of said other denomination to move said fourth member and the first member therewith.

2. In a vending machine, a movable member formed with three shoulders, a member adapted to engage one of the shoulders to prevent movement of said movable member and releasable upon insertion into the machine of a coin of one denomination, a second member having means to engage a second shoulder to prevent movement of said movable member and releasable upon insertion into the machine of a coin of another denomination, a third member having means to engage a third shoulder and releasable upon insertion into the machine of a second coin of said other denomination, said second and third members having means to release said second and third members from the second and third shoulders upon insertion into the machine of a second coin of the first denomination, a fourth member, means to connect the fourth member to the first member for simultaneous movement, and means on the fourth member to move said fourth member and the first member therewith upon insertion into the machine of a fourth coin of said other denomination, adjustable means on said interconnecting member normally inoperative to move said third member but adapted to be adjusted to a position where it will move said third member to release said third shoulder upon movement of said first and fourth members, to release said third member from said third shoulder.

3. In a vending machine, a movable member formed with three shoulders, a member adapted to engage one of the shoulders to prevent movement of said movable member and releasable upon insertion into the machine of a coin of one denomination, a second member having means to engage a second shoulder to prevent movement of said movable member and releasable upon insertion into the machine of a coin of another denomination, a third member having means to engage a third shoulder and releasable upon insertion into the machine of a second coin of said other denomination, said second and third members having means to release said second and third members from the second and third shoulders upon insertion into the machine of a second coin of the first denomination, a fourth member, means to connect the fourth member to the first member, means on the fourth member to move said fourth member and the first member therewith upon insertion into the machine of a fourth coin of said other denomination, adjustable means on said interconnecting member normally inoperative to move said third member but adapted to be adjusted to a position where it will move said third member to release said third shoulder upon movement of said first and fourth members, to release said third member from said third shoulder, and normally inoperative adjustable means to move said first member upon in-

sertion into the machine of three coins of said other denomination to release said first member from said first shoulder.

4. In a vending machine, a movable member formed with three shoulders, a member adapted to engage one of the shoulders to prevent movement of said movable member and releasable upon insertion into the machine of a coin of one denomination, a second member having means to engage a second shoulder to prevent movement of said movable member and releasable upon insertion into the machine of a coin of another denomination, a third member having means to engage a third shoulder and releasable upon insertion into the machine of a second coin of said other denomination, said second and third members having means to release said second and third members from the second and third shoulders upon insertion into the machine of a second coin of the first denomination, a fourth member, means to connect the fourth member to the first member, means on the fourth member to move said fourth member and the first member therewith upon insertion into the machine of a fourth coin of said other denomination, a member movably mounted on said fourth member, and means to fix said movably mounted member to said fourth member, said movably mounted member having means, operative when said movable member is fixed to the fourth member to move the fourth member and the first member therewith, upon insertion into the machine of three coins of said other denomination to release said first member from the first shoulder.

5. In a vending machine, a movable member formed with three shoulders, a member adapted to engage one of the shoulders to prevent movement of said movable member and releasable upon insertion into the machine of a coin of one denomination, a second member having means to engage a second shoulder to prevent movement of said movable member and releasable upon insertion into machine of a coin of another denomination, a third member having means to engage a third shoulder and releasable upon insertion into the machine of a second coin of said other denomination, said second and third members having means to release said second and third members from the second and third shoulders upon insertion into the machine of a second coin of the first denomination, a fourth member, means to connect the fourth member to the first member, means on the fourth member to move said fourth member and the first member therewith upon insertion into the machine of a fourth coin of said other denomination, a member movably mounted on said fourth member, means to fix said movably mounted member to said fourth member, said movably mounted member having means, operative when said movable member is fixed to the fourth member to move the fourth member and the first member therewith, upon insertion into the machine of three coins of said other denomination to release said first member from the first shoulder, and means on said interconnecting member disposed just below the third member and adapted in one position to clear said third member so as not to move the same, when said first and fourth members are moved, and in another position to engage said third member to move the same when said first and fourth members are moved, for releasing the third member from the third shoulder.

6. In a vending machine, a movable member

formed with three stops, a member having means to engage one of said stops to prevent movement of said movable member and also having means to contact a coin of one denomination inserted into the machine to release said engaging means from said stop, a second member having means to engage the second stop to prevent movement of said movable member and also having means to contact a coin of another denomination inserted into the machine, to release the engaging means of the second member from said second stop, a third member having means to engage the third stop and also having means to contact a second coin of said other denomination inserted into said machine, to release the engaging means of the third member from the third stop, said second and third members having additional means to concurrently contact a second coin of the first denomination inserted into the machine to simultaneously release the engaging means of the second and third members from said second and third stops.

7. In a vending machine, a movable member formed with three shoulders, a member adapted to engage one of the shoulders to prevent movement of said movable member and releasable upon insertion into the machine of a coin of one denomination, a second member having means to engage a second shoulder to prevent movement of said movable member and releasable upon insertion into the machine of a coin of another denomination, a third member having means to engage a third shoulder and releasable upon insertion into the machine of a second coin of said other denomination, said second and third members having means to release said second and third members from the second and third shoulders upon insertion into the machine of a second coin of the first denomination, a fourth member, means to connect the fourth member to the first member, means on the fourth member to move said fourth member and the first member therewith upon insertion into the machine of a fourth coin of said other denomination, and means on said interconnecting member disposed just below the third member and adapted in one position to clear said third mem-

ber so as not to move the same, when said first and fourth members are moved, and in another position to engage said third member to move the same when said first and fourth members are moved, for releasing the third member from the third shoulder.

8. In a vending machine, a movable member formed with two stop means, a first member having means to engage one of said stop means to prevent movement of said movable member and having means to contact a coin inserted into the machine, to release said engaging means from said stop means, said movable member having a second stop means, a second member having means to engage the second stop means to prevent movement of said movable member and having means to contact another coin inserted into the machine to release said last engaging means from said second stop means, said first and second members each having additional means to concurrently contact still another coin inserted into the machine to concurrently release said engaging means of said first and second members from both said stop means.

9. In a vending machine, a movable member, stop means on said movable member, a first member having means to engage said stop means to prevent movement of said movable member, means on said first member to contact a coin inserted into the machine to release said engaging means from said stop means, a second member, means to connect said first and second members together for simultaneous movement, means on the second member to contact a coin inserted into the machine to cause movement of said second member together with said first member, a member movably mounted on the second member, means to fix said movably mounted member to said second member, in a predetermined position, said movably mounted member having means operative only when said movable member is fixed to said second member in said predetermined position, to engage a coin inserted into the machine to cause movement of said second member and the first member therewith.

LOUIS STEINER.
